UNITED STATES PATENT OFFICE

2,229,224

ELECTRIC ACTIVATION OF TOE-LASTING
CEMENT

Walter S. Rogers, Falmouth, Mass., assignor to
United Shoe Machinery Corporation, Borough
of Flemington, N. J., a corporation of New
Jersey

Application April 12, 1940, Serial No. 329,282

6 Claims. (Cl. 12—14)

This invention relates to machines for lasting shoes by means of cement and more particularly for activating the lasting cement around the toe end of a shoe, by means of a high-frequency electrostatic field.

In cement lasting it is common to provide a film of adhesive between the margin of the insole and the overlasted margin of the upper and this cement may be of the thermoplastic variety which is allowed to become hard and non-tacky before the shoe is presented to the lasting machine, and which will be activated in that machine to hold the overlasted upper in position. It is not entirely satisfactory to activate the cement before the upper is lasted over the insole, and the application of heat after the lasting operation by any ordinary heating device is impractical because of the necessity of transferring the heat through the leather of the upper or the insole.

Accordingly, an object of this invention is to provide apparatus for the activation of the lasting cement by means of a high-frequency electrostatic field, thus enabling the heat to be produced directly in the cement and at any desired time in the cycle of the lasting operation.

One particular application of the invention as illustrated herein concerns the activation of the cement in shoes being treated in a power-operated toe-lasting machine, and takes advantage of the fact that shoes which are to be lasted in one of these machines are frequently constructed upon lasts having metal toe plates attached to the bottom of the lasts. As illustrated, therefore, such a toe plate is used as one of the electrodes, while an element of the machine located outside the shoe is utilized as the other electrode. The intended purpose will be accomplished if this machine element is in such a position that the field set up between it and the toe plate includes the film of cement in the shoe. Consequently, the wiper plates of the lasting machine have been employed for this purpose and are connected to one side of an oscillator which forms the source of electricity. The other side of the oscillator is connected to the toe plate by locating pins which pass through apertures in the insole to engage suitable recesses in the last and which at the same time engage the toe plate.

These and other features of the invention will best be understood from a consideration of the following specification taken in connection with the accompanying drawing, in which

Fig. 1 is a vertical section through the shoe—

engaging portion of a toe-lasting machine to which the invention has been applied;

Fig. 2 is a detail view showing the position of the parts at the completion of the lasting operation;

Fig. 3 is a plan view showing the overlasted shoe upper held in position by wipers; and

Fig. 4 is a transverse section through the toe end of a shoe with the parts of the machine in the positions illustrated in Fig. 2.

The invention has been applied to a machine of the type illustrated in Letters Patent of the United States No. 2,224,146, granted December 10, 1940, upon the application of F. C. Eastman for improvements in Lasting machines, and only so much of the machine has been shown herein as is necessary to a description of the present invention.

The machine is shown as operating upon a shoe built upon a last L which is provided with a metal toe plate P. This plate is provided with a pair of metal sockets 10 and is flush with the bottom of the last, lying beneath the insole I over which the upper U is to be lasted. A shoe S will be located in the machine by raising the bottom of the insole into engagement with a plate 12 of insulating material, such as Textolite or the like, which is supported through interposed parts upon a plunger 14 vertically adjustable in the frame 16 of the machine by means of a threaded stop 18. The plate 12 must be of a size suited to the size of the shoe to be lasted and, accordingly, it is made removable for exchange with plates of different size and is provided with an apertured stud 20 received in a socket in a metal member 22. The member 22 comprises top and bottom flanges 23 and 25 (Fig. 4) interconnected by a vertical web in which there is slidably mounted a spring plunger 24 (Fig. 1) which cooperates with the stud 20 to lock the plate 12 in position on the carrier. The member 22 is attached by screws 26 (Fig. 2) to the bottom of a block 28 of insulating material which, in turn, is attached by screws 30 to a flange 31 on the lower end of the plunger 14.

Shoe locating pins 34, such as have been employed in the lasting machine of the Eastman patent No. 2,224,146, are secured in the member 22 and extend through apertures 36 (Fig. 4) in the plate 12 and apertures 38 in the insole I into contact with the sockets 10 which may be made a part of the toe plate P. The high tension side of an oscillator (not shown) is connected to the member 22 by a lead 40, and the locating pins 34 both locate the shoe in proper

55 50 45 40 35 30 25 20 15 10 5

angular position in the machine and serve to convey the electric current to the metal toe plate P upon the bottom of the last.

In carrying out the lasting operation, the upper U is first drawn upwardly and outwardly with respect to the shoe by means of grippers 50 in a carrier 52 which is pivotally supported at 54 at the end of an arm 56 carried on a rod 58 so attached to the frame of the machine that the arm 56 may swing around the center of the rod. During this lasting operation the toe end of the shoe is held up against the locating plate 12 by means of a toe rest 42 having a pad 44 which overlies a rigid member 46. The toe rest is raised automatically, substantially at the beginning of the operation of the machine, and in connection with a heel band (not shown) serves to clamp the shoe in position in the machine.

It will be understood that both side and end grippers 50 are provided, but that only the end gripper is herein illustrated. Up-and-down movements of the gripper carrier 52 are imparted through a cam-operated link 60, and in-and-out swinging movements of the gripper carrier are imparted through a cam-operated link 62, this arrangement being more fully described in Letters Patent of the United States No. 2,160,846, granted June 6, 1939, upon the application of F. C. Eastman et al.

30 The margin of the toe end of the insole is held down in firm engagement with the last by means of a curved member 70 which extends around the forward end of the locating plate 12 to overlie the margin of the insole, and is itself preferably constructed of insulating material such as is employed elsewhere in the machine. This curved holddown member 70 is attached to a plug 72 in the lower end of a vertical carrier 74 which is supported for up-and-down movements by means of parallel links 76 extending between the carrier 74 and the flange 31 on the lower end of the plunger 14. It is also supported by the arms of a yoke 78 pivotally mounted on the plunger 14 and having an upstanding portion 45 providing a shoulder 80. The holddown member 70 is held in engagement with the insole by means of a spring 82 extending between the upper end of the carrier 74 and a pin on the frame of the machine.

50 The machine is also provided with wipers 90, supported in wiper carriers 92 and arranged for movement toward the toe end of the shoe, to engage the side of the shoe and then to upwipe the upper U. After this the wipers 90 are carried in over the insole I against the upper as it is tensioned by the grippers 50 and similar side grippers (not shown). These grippers are released at the desired point in the cycle by the action of a cam-operated lever 94 on a plunger 96 sliding within the gripper carrier 52. It will be noted that the lower outside margin of the holddown member 70 is provided with a bevel 98 so that said member in cooperation with the wipers 90 serves as a retarder to cause the upper 65 to be wiped more tightly and smoothly inward over the insole. During the inward movement of the wipers the grippers are permitted to swing inwardly toward the shoe, and in order that there may be no interference between the holddown 70 and the grippers, the holddown is lifted out of their way. Thus, as the holddown is raised by the engagement of the wipers with the beveled surface 98, the shoulder 80 on the yoke 78 is raised to a point where it will be engaged by a notch 100 in a bar 102. This bar is held down

against a surface 104 on the yoke 78 by means of a spring 106 and is moved laterally by means of a cam-operated arm 108 to raise the holddown against the tension of the spring 82.

The arrangement of the machine is such that it comes to rest after the upper has been completely wiped in and the wipers 90 have been depressed to hold the overlasted upper firmly in engagement with the insole. At that time, for example, power is supplied to the electrodes 10 either automatically or manually by way of the lead 40 connected to the positioning pins 34 and a lead 110 here shown diagrammatically as connected directly to one of the wipers. Actually, however, it will be satisfactory to connect this lead to any portion of the frame of the machine, since it is preferably connected to the ground side of the oscillator and may thus be safely grounded on the frame of the lasting machine. After an interval of only a few seconds the 20 cement will have been activated by the field and will, as soon as the field is cut off, return to its solid state to cause the adhesion of the upper to the insole. The machine will then proceed with the completion of its cycle, withdrawing the 25 wipers and depressing the toe rest 42 etc., permitting the removal of the shoe from the machine.

Having thus described my invention, what I claim as new and desire to secure by Letters 30 Patent of the United States is:

1. In a machine for lasting shoes which have been assembled on lasts having metal toe plates, supporting means for the toe portion of an inverted shoe, lasting means engaging the overlasted upper on the bottom of the shoe, means for connecting one side of said means to one side of a high-frequency circuit, and means for connecting the other side of said circuit to a toe plate on the last of said shoe, thereby to set up 40 an electrostatic field localized at the toe end of the shoe.

2. In a machine for cement lasting a shoe upper to an insole on a last, means for activating thermoplastic lasting cement comprising a lasting device for engaging the overlasted margin of the upper of a shoe, means connecting said device to one side of a high-frequency circuit, and means for connecting the other side of said circuit to a toe plate carried on the last within the 50 shoe.

3. In a machine for cement lasting shoes with apertured insoles which have been assembled on lasts having metal toe plates and which have been provided with an adhesive between said 55 insole and the overlasted upper, a lasting device for conforming the upper to the last and drawing it over the margin of the insole, means for connecting one side of a source of high-frequency current to said lasting device, and means for connecting the other side of said source to the toe plate.

4. In a machine for cement lasting shoes which have been provided with an adhesive between an insole embodied in said shoe and the 65 overlasted margin of the upper thereof, a lasting device which in one position of operation engages the overlasted margin of the upper, means for connecting said lasting device to one side of a high-frequency circuit, an electrode associated 70 with another portion of the shoe constructed and arranged to pass an electrostatic field through said adhesive, and means for connecting said electrode to the other side of said source.

5. In a lasting machine for shoes with aper- 75

tered insoles and which have been assembled on lasts having apertured metal toe plates, shoe positioning and gripping means comprising a presser member acting against the outer face of an insole and provided with a locating pin adapted to pass through an opening in the insole to engage an aperture in said plate and make contact with the plate, lasting mechanism comprising a wiper movable to wipe the upper over a margin of the insole and to press it into position thereupon, said shoe having a film of cement between the insole and the overlasted upper, and means for connecting a source of high-frequency current to said locating pin and said wiper thereby to produce an electrostatic field between the wiper and the plate and passing through the

cement to activate the latter to stick the upper in lasted relation.

6. In a machine for cement lasting shoes which have been assembled on lasts having metal toe plates and which have been provided with an adhesive between an apertured insole embodied in said shoe and the overlasted upper thereof, shoe-supporting means, lasting mechanism comprising upper-tensioning means and upper-wiping means adapted to press the overlasted upper into firm engagement with the insole, means operating through the aperture in said insole to connect a toe-plate with one side of a high-frequency circuit, and means for connecting the other side of said circuit to one portion of said lasting mechanism.
